DESIGN FOR A COAL BURNING STOKER

Thomas H. Banfield, Portland, Oreg., assignor to Iron Fireman Manufacturing Company, Portland, Oreg.

Application September 11, 1933. Serial No. 49,233

Term of patent 14 years

To all whom it may concern:

Be it known that I, THOMAS H. BANFIELD, a citizen of the United States, residing at Portland, county of Multnomah, State of Oregon, have invented a new, original, and ornamental Design for Coal Burning Stokers, of which the following is a specification, reference being had to the accompanying drawing, forming part thereof.

The figure is a perspective view of the stoker casing showing my new design.

The appearance of the opposite side of the device is substantially the same as is shown on the drawing, except that the conveyor section is in the foreground.

I claim:

The ornamental design for a coal burning stoker, as shown and described.

THOMAS H. BANFIELD.
